UNITED STATES PATENT OFFICE.

SAMUEL B. WILLIAMS, OF BROOKLYN, NEW YORK, AND EARL S. GIBSON, OF RIDGEWOOD, NEW JERSEY, ASSIGNORS TO WESTERN ELECTRIC COMPANY, INCORPORATED, OF NEW YORK, N. Y., A CORPORATION OF NEW YORK.

TELEPHONE-EXCHANGE SYSTEM.

Application filed November 21, 1924. Serial No. 751,235.

This invention relates to telephone exchange systems and more particularly to systems employing machine switching apparatus controlled by operators for establishing connections.

The object of this invention is an improved method of routing conversational connections in a system comprising offices having automatic switching equipment under the control of operators.

A feature of the invention relates to a system having switches controlled by senders and markers, the markers being arranged to receive variable settings from the senders in accordance with the manipulation of an operator's keyboard to determine the routing of a call through different tandem offices to a desired office.

Other features and advantages of the invention will become more thoroughly understood from a consideration of the following detailed description and the appended claims.

Referring to the drawings:

Figs. 1 to 11 inclusive, arranged in the order illustrated in Fig. 13, disclose a sufficient amount of a telephone exchange system embodying features of this invention to enable an understanding thereof.

Fig. 1 shows a trunk incoming to an operator's position together with one of a number of cord circuits at said position.

Fig. 2 shows one of a number of district selector switches which hereinafter will be called semi-mechanical district selectors.

Fig. 3 shows the operator's telephone set together with certain recording equipment at her position.

Fig. 4 illustrates an operator's keyboard for setting up the records of calls.

Fig. 5 shows diagrammatically a sender selector switch, and also illustrates in detail an impulse controlling and sending equipment associated with the operator's position and common to all trunks in such position.

Figs. 6 and 7 illustrate a portion of an operator's recording sender. Fig. 6 shows the control relays of the sender while Fig. 7 shows the routing and code registers and illustrates diagrammatically the numerical register.

Fig. 8 shows a sender connector for connecting the senders to the markers.

Figs. 9 and 10 illustrate one of the mark-

ers serving to control the semi-mechanical switch and other similar switches.

Fig. 11 illustrates a frame and trunk connector for associating the marker with the district switches.

Fig. 12 shows a general layout of the system with the various apparatus shown in simplified form. The purpose of this figure is to show the relation of the various apparatus to each other and to enable a general understanding of the operation to be had.

The equipment illustrated in the drawing is designed especially for the "A" operator's board in an automatic telephone system and serves to handle calls which for one reason or another are routed to the "A" operator's position. The calls routed to this position are received on trunks, such as the trunk 100, which may lead from the terminals of a regular district selector switch. The operator answers these calls by inserting the plug into one of her trunk circuit jacks and converses with the calling subscriber. Having ascertained his wants she proceeds to write up the number of the called line on her keyboard.

The above sending equipment shown in Fig. 5 is thereupon brought into action and transmits impulses through the sender selector switch 500 to set the registers of the sender shown in Figs. 6 and 7.

The sender is then associated with an idle marker through the sender connector 800 and the routing and code records transmitted into the marker. Thereupon the marker is associated with the particular district selector 200 in which appears the trunk 132 terminating in the cord circuit employed by the operator. The district selector 200 is then controlled to select an idle trunk leading in the proper direction.

The call may run to a distant office which may be reached through any one of a number of tandem offices. Accordingly the operator's keyboard is equipped with a number of tandem route keys in order that she may determine a particular tandem office through which the call should be extended. These route keys 400 are shown in Fig. 4. Moreover the operator's position is equipped with three sets of code or office keys 401, 402, 403, and also with numerical keys 404 and station keys 405. Only a portion of each row of these keys is illustrated.

The register senders accordingly are provided with a route register 700, office or toll registers 701, 702, 703 and the numerical registers 704. Inasmuch as the numerical portion of the designation is not particularly concerned in this invention, the corresponding numerical registers have not been illustrated in detail.

In the marker there are provided four registers 900, 901, 902 and 903 each corresponding respectively to the route and code registers of the senders. The marker is therefore equipped with a translator 905 which consists of three banks of multi-contact relays only a portion of each bank being shown. The first bank for instance, includes relays 906, 907, etc., the second bank includes relays 908, 909, etc., and the third bank includes relays 910, 911, 912, etc. The purpose of this translator will be brought out in detail hereinafter.

Moreover the marker includes a testing relay set 1000, comprising a series of doubly wound test relays for testing the conditions of the idle links of the district selector switches 200 and the condition of the outgoing trunks in any desired group.

The selector switch 200 and the sender selector switch 500 are of the coordinate type such as shown and described in U. S. Patent No. 1,515,735 issued November 18, 1924, to C. L. Goodrum and J. N. Reynolds, and in U. S. Patent No. 1,517,331 issued December 2, 1924, to S. B. Williams.

The register senders and the markers are of the general type as shown and described in U. S. Patent No. 1,517,331 issued December 2, 1924, to S. B. Williams, and in U. S. Patent No. 1,543,967 issued June 30, 1925, to S. B. Williams and E. S. Gibson.

Before proceeding with a detailed description of the operation a general description of the system will be taken up in connection with the diagrammatic illustration in Fig. 12. This figure shows subscribers' lines, such as line 1200, terminating in line switches 1201. The initiation of a call causes the operation of the line switch 1201 to select a trunk leading to a subscriber's district selector switch 1202, and also causes the operation of the sender selector switch 1214 to associate an idle subscriber's sender 1215 with the calling line. After the subscriber has transmitted the record to the sender 1215 said sender is connected through the sender connector 1216 to an idle outgoing marker 1217.

In case the subscriber has dialed a wrong number or has dialed the operator's number, the marker 1217 after having been associated with the district switch 1202 and with the proper group of trunks by means of the frame and trunk connectors 1218 and 1219 respectively, causes the operation of the district selector switch 1202 to select an idle

trunk 1204 terminating in the jack 1205 at the "A" operator's position. The "A" operator's attention is attracted and she responds by inserting the plug of a cord circuit 1206 in the jack and obtains the number orally from the calling subscriber. The insertion of the plug in the jack initiates the operation of the sender selector 1231 and the cord circuit 1206 is automatically associated with the operator's sender 1232. 75

Having obtained the number the operator records the same on her keyboard 1230. The keyboard 1230 is associated through a connecting device 1236 with the cord circuit 1206 and the record is transmitted 80 through the sender selector 1231 and recorded in the operator's sender 1232. After the record is recorded the sender 1232 is connected to the operator's marker 1233 and a portion of the record is transferred from the 85 sender to the marker.

If the wanted line is located in a distant office 1228 which may be reached through one or more tandem offices 1226, 1227, etc., the operator must decide through which one 90 of these tandem offices the connection should be reached. If it is desired to route the connection through the tandem office 1226 she depresses the proper route key which determines the corresponding setting of the route 95 register in the operator's marker 1233. Thereafter the marker is associated through the frame and trunk connectors 1234 and 1235 with the semi-mechanical district switch 1207 and with the group of trunks leading to 100 the tandem point 1226. The switch 1207 is controlled by the marker and the connection is extended over an idle trunk 1224 to the tandem office 1226.

Thereafter the office record may be transferred from the sender 1232 over the trunk 1224 by means of code impulses and received in a corresponding sender in the tandem office 1226. This sender may control the switches in the tandem office to the sender 110 connected in the desired office 1228 where the connection is completed to the calling subscriber's line 1229. 105

Should the operator desire to extend the call through the tandem office 1227 she depresses the key representing this tandem office and the connection is now routed to trunk 1225 through the tandem office 1227 to the desired line 1229 in the office 1228. The manner in which records may be sent 115 from a sender in one office to a sender in a different office is illustrated and described in U. S. Patent No. 1,543,967, issued June 30, 1925, to S. B. Williams and E. S. Gibson. 120

It may happen that the calling subscriber wishes connection with a toll line. In this case the operator writes up the number on her keyboard causing the operation of the semi-mechanical district selector 1207 to se- 125 130

lect trunk 1208 leading to a subscriber's district 1203. Thereafter the operator's sender is associated with an outgoing marker 1217 which controls the district selector switch 1203 to extend the connection over a trunk 1209 to the incoming switch 1210. The subscriber's sender is then associated with the incoming marker 1220 which in turn controls the incoming and final switches 1210 and 1212 to complete the connection over the trunk 1211 to the called line 1213. The manner in which this connection is routed through the incoming and final switches is fully described in U. S. Patent No. 1,600,444 issued September 21, 1926, to S. B. Williams and E. S. Gibson.

Detailed description of the operation.

It will be assumed that a connection has been extended to the A operator's position and the operator upon answering ascertains that the called subscriber desires to converse with a subscriber at a distant office which may be reached through a tandem office.

The incoming connection is extended over the trunk 100 from a preceding switch in the well known manner and a signal (not shown) is given to the A operator, advising her that a call is awaiting her attention. The operator seizes the plug 102 of an idle cord circuit 103 and inserts it in the jack 101 of the calling trunk. The insertion of the plug in the jack causes the operation of relay 127 in a circuit from battery, through the winding of said relay, the sleeve of the plug 102, sleeve of the jack 101, over the sleeve conductor of the incoming trunk to ground.

The relay 127 causes the operation of relays 130 and 131 individual to the cord circuit 103 in a circuit from ground, through the back contact of relay 126, outer right contact of relay 127, inner right contact of relay 128, windings of relays 130 and 131, left contact of relay 114, resistance 301, to battery. Relay 130 completes a circuit from battery, above traced, through its winding and inner right front contact, through the winding of relay 126, to ground. Relay 126, however, does not operate at this time, since its winding is shunted by the above traced circuit. The relays 130 and 131 serve to associate the operator's key set with the trunk taken for use.

Relay 131 causes the operation of relays 105, 128 and 115 in circuits leading from battery, through the windings of these relays in parallel, to ground at the outer right front contact of relay 131. The relay 105 connects the operator's telephone set (shown in Fig. 3) to the tip and ring conductors of the cord circuit 103, placing her set in conversational connection with the calling subscriber's line.

Relay 115 locks in a circuit from battery,

through its left front contact, contact of relay 113, right front contact and winding of relay 115, resistance 133, to ground at the left contact of relay 127. It will be noted that relay 113 was operated at this time in series with the left winding of the repeating coil 104, including the loop of the calling subscriber's line. The locking circuit above traced for relay 115 serves to shunt the supervisory lamp 129, preventing the same from illuminating.

Relay 128 locks in a circuit from battery, through its left winding and inner left contact, left back contact of relay 122, to ground at the left contact of relay 127. Relay 128 opens the shunt around the winding of relay 126, and this latter relay operates in series with relays 130 and 131.

At this stage of the connection, green supervisory lamp 121 is illuminated in a circuit from battery, through said lamp, resistance 120, left back contact of relay 119, outermost contact of relay 118, middle right back contact of relay 123, to ground at the contact of relay 127.

The relay 131 also causes the operation of the relay 501 which is associated with the sender selector 500 and is individual to the particular cord circuit 103 which the operator has taken for use. This circuit may be traced from battery, through the winding of relay 501, thence through the inner upper contact of relays 110 and 109, contact of relay 125, to ground at the contact of relay 127. Relay 501 initiates the operation of the sender selector switch 500 which serves to associate the cord circuit and operator's keyboard with an idle register sender.

While the sender selector is operating, it places ground potential on the conductor 515, which results in the closure of a circuit through the left contact of relay 612, right contact of relay 617, outer left contact of relay 618, winding of relay 619, to battery. Also during the operating period of the sender selector 500, the vertical magnet 516 completes a circuit for operating the frame test relay 618. This circuit may be traced from battery, through the winding of relay 618, left contact of relay 619, conductor 620, to ground at the contact of magnet 516.

The frame test relay 618 causes the operation of the holding relay 606 in a circuit from battery, through the winding of the latter relay, inner left contact of relay 618, and thence to ground over the circuit above traced. Relay 606 locks through its left contact, to ground through the right contact of relay 612. The relay 110 in the operator's cord circuit is now operated in series with the relay 607 in the sender. The circuit for this purpose may be traced from battery, through the winding of relay 110, right contact of relay 119, conductor 134, through the sender selector 500, conductor 130

515, left contact of relay 612, winding of relay 607, conductor 621, to ground at the contact of relay 606.

- 5 Relay 607 causes the operation of relay 608, which in turn locks to the grounded conductor 621. Relay 110 in the cord circuit opens the circuit of relay 501, which releases. Relay 110 also causes the illumination of the white supervisory lamp 111 in a circuit from battery, through said lamp, resistance 112, front contact of relay 110, to ground at the outer back contact of relay 123.

The apparatus is now ready for the operator to set up the designation of the wanted subscriber's line on her keyboard. If the call is to be routed to a given tandem office, the operator first depresses the route key 406 which is individual to this particular tandem office. She then depresses the office code keys 407, 408 and 409 which represent the number of the called office containing the desired line. Furthermore, she depresses the proper combination of numerical keys 404 representing the number of the wanted line, and, if the wanted subscriber is on a party line, one of the stations key 405. If the wanted line is a direct line, however, she depresses the start key 410.

- 5 The start key 410 causes the operation of relay 504 in a circuit from battery, through the winding of this relay, conductor 519, through the contact 412 which is common to the row of keys 405 and operates when any one of these keys is depressed, conductor 413, to ground. Relay 504 causes the operation of relay 124 in a circuit from battery, through the winding and contact of the latter relay, conductor 135, inner left contact of relay 131, conductor 136, to ground at the contact of relay 504. Relay 124 locks through its front contact to ground at the left contact of relay 127.

- 45 Relay 504 causes the operation of relay 507 in a circuit from battery, through the winding of relay 507, lower back contact of relay 508, conductor 520, back contact of relay 506, inner back contact of relay 505, at the contact of relay 509. Relay 507 operates and connects the route keys 400 to the conductors 415, which lead through the sender selector 500 to the register sender.

- 55 The impulse generating relays 502 and 503 are now set in operation to measure intervals of time for the purpose of creating codes of impulses in accordance with the condition of the operator's keyboard. These relays are made slow to operate and to release. The relay 502 is first operated in a circuit from battery, through resistance 521, winding of said relay, right back contact of relay 503, left normal contact of relay 505, conductor 523, upper back con-

tact of relay 508, front contact of relay 507, conductor 524, to ground at the back contact of relay 540. Relay 502 operates after an interval and causes the operation of relay 503 in a circuit from battery, through resistance 522, winding of relay 503, right front contact of relay 502, conductor 525, to ground at the contact of relay 519. Relay 503 operates and closes a shunt circuit for relay 502 from battery, through resistance 521, inner left front contact of relay 503, to the grounded conductor 525. Relay 502 after an interval releases and closes a shunt circuit for relay 503. This circuit may be traced from battery, through the resistance 522, outer right back contact of relay 502, to the grounded conductor 525. Relay 503 releases after an interval. In this manner, the relays 502 and 503 are operated and released in succession to measure intervals of time for the creation of code impulses.

Relay 507 on operating, completes a locking circuit for itself from battery, through its winding and inner left contact, conductor 526, winding of relay 506, left front contact of relay 502, to the grounded conductor 525. Relay 506, however, does not operate yet, since its winding is shunted by the previously traced circuit for relay 507.

As soon as relay 503 operates as above described, slow-release relay 505 is energized in a circuit from battery, through the winding of the latter relay, outer left contact of relay 503, to the grounded conductor 525. Relay 505 operates and another branch of the above traced locking circuit for relay 507 is now completed through the inner left front contact of relay 505, outer left front contact of relay 503, to the grounded conductor 525. Relay 506, however, still remains de-energized. Relay 505 causes the operation of relay 508 by means of a circuit from battery, through the right contact of relay 505, conductor 527, upper winding of relay 508, outer left contact of relay 507, to the grounded conductor 524. Relay 508 operates and locks through its lower winding to the grounded conductor 524. Relay 508 in operating opens the shunt around the winding of relay 506 and this latter relay now operates in series with relay 507. At the end of the cycle, relay 503 releases as above related and opens the circuit of relay 505, which becomes deenergized. Relay 503 in releasing at this time, opens the circuit including relay 507 and relay 506, and these two latter relays become deenergized. Relay 507 disconnects the routing key set 400 from the sender. The relay 505 is made slow-to-release in order to allow sufficient time for the disassociation of one row of keys before the association of another.

Since the routing key 406 is depressed, a circuit is completed for sending a code im-

- pulse to the sender during the period that the impulse relays 502 and 503 are operating as above explained. This circuit may be traced from ground, through the high resistance 411, right contacts of key 406, conductor 416, through the outer right front contact of relay 507, conductor 528, outer left contact of relay 131, conductor 529, through the sender selector 500, conductor 622, contact of relay 623, windings of relays 604 and 605, to battery. Relay 604 is marginal, and therefore does not operate in series with the high resistance 411. Relay 605, however, becomes energized in the circuit traced.
- 5 15 Relay 605 operates the relay 721 in a circuit from battery, through the winding of the latter relay, right back contact of relay 722, conductor 729, normal contact of relay 609, to ground at the contact of relay 605.
- 20 Relay 721 operates and closes a holding circuit for itself from battery, through its winding and inner contact, thence through the winding of relay 609, to ground at the contact of relay 605. Relay 609, however, being shunted, does not operate. Relay 721 connects the conductors 730 which lead from the impulse receiving relays of the sender through to the relays of the route register 700.
- 25 30 Since the route key 406 is operated, none of the relays 600, 601, 602, 603 or 604 is energized, and consequently none of the four relays 705, 706, 707 or 708 of the register 700 is operated. The relay 722 is now energized in a circuit from battery, through its winding, lower contact of relay 721, conductor 731, back contacts of relays 601, 603 and 602, conductor 625, to ground at the contact of relay 605. Relay 722 locks over conductor 40 732, to the grounded conductor 621. Relay 722 removes the shunt and permits relay 609 to operate in series with relay 721.
- 35 The relays 502 and 503 perform another cycle, during which time the impulses are sent to the sender in accordance with the record on the first set of code keys 401 of the operator's keyboard. When the relay 503 releases, as above described, the relay 509 is operated in a circuit from battery, through its winding, lower contact of relay 510, lower front contact of relay 508, conductor 520, thence through back contacts of relays 506, 505 and 503 to the grounded conductor 525. Relay 509 operates and closes a locking circuit 45 in series with relay 506, as above described. Relays 502, 503, 505 and 506 operate and release in the manner described, causing the operation of relay 510 and consequently the release of relay 509.
- 50 55 During the interval measured by the impulse relays, code impulses are sent to the sender to cause the operation of certain of the impulse receiving relays 600, 601, 602, etc. It will be noted that relay 605, which 60 65 was previously operated in connection with the routing digit, was released when relay 507 became deenergized. The fact that the key 407 is depressed, results in the operation of relay 601 in a circuit from battery, through the winding of said relay, winding 70 of relay 600, conductor 627, through the sender selector 500, conductor 530, through contacts of relay 131, conductor 418, inner right contact of relay 509, conductor 531, left contacts of key 407, high resistance 411, 75 to ground. Due to the high resistance 411, relay 600 does not operate in this circuit. Still another circuit is closed for operating relay 605, and may be traced from battery, through the winding of said relay, winding 80 of relay 604, and thence as above described to conductor 528 through contact of relay 509, conductor 532, right contacts of key 407, high resistance 411, to ground. Relay 605 operates in this circuit, but relay 604 remains 85 inert.
- 90 The first code register 701 is now set in accordance with the operated condition of impulse relay 601. In the manner just above described, the relay 723 is operated to extend the impulse conductor 730 through to the register 701. Relay 709 is operated in a circuit from battery, through its winding, contact of relay 723, thence through the right front contact of relay 601 and back 95 contacts of relays 603 and 602, to ground over conductor 625. Relay 709 locks to the grounded conductor 732. Relay 724 is operated and, removing the above described shunt, permits relay 609 to operate in series 100 with relay 723.
- 105 At the end of the cycle measured by the impulse relays 502 and 503 relay 509 is released as above described and relays 601 and 605 become deenergized, causing the release of relay 722 and the preparation of the circuit for the receipt of the next digit.
- 110 In a similar manner, the impulse relays 502 and 503 perform repeated cycles and the successive relays 511, 513, etc., are energized to associate each successive set of keys at the operator's keyboard with the register sender, and code impulses are transmitted to the sender in accordance with the particular key depressed in each row. Marginal relays 600, 602 and 603 are operated or remain inert on each occasion according to whether a low or high resistance is included in series therewith. These impulse receiving relays in the sender are associated 115 with the successive registers 702 and 703 and with the numerical registers 704, and these registers are operated in accordance with the changes involved. It will be found from inspection that, due to the fact that code 120 keys 408 and 409 are depressed, relay 733 of the register 702 and relays 734 and 735 of register 705 are operated. Similarly, the numerical registers 704 are operated in accordance with the depressed condition of the 125 130

numerical keys 404. The manner in which the register relays shown in Fig. 7 operate to receive the digits as wanted numbers, is more fully described and illustrated in U. S. Patent No. 1,517,331, issued Dec. 2, 1924, to S. B. Williams.

After all the digits have been transmitted from the keyboard and relay 533 has been energized, and when relay 533 again releases, a circuit is closed for operating relay 540. This circuit may be traced from battery, through the winding of relay 540, thence through front contacts of relay 533 and all preceding relays, over conductor 520, to ground as above traced. Relay 540 locks through its left front contact and thence through back contacts of relays 507, 509, 511, 513, etc., through contacts of any operated key in the corresponding row, to ground. Relay 540 at its right contact, closes operating circuits for the key release magnets shown at the top of Fig. 4. These magnets cause the release of all depressed keys in their corresponding rows, and when all keys on the board have been released the key release relay 540 becomes deenergized. Thus the operator's keyboard is restored to normal.

When the last digit of the office code has been recorded in the sender, the relay 728 operates and closes a start circuit for the sender connector 800, which acts to connect the sender with an idle marker. The start circuit may be traced from the grounded conductor 732, through the contact of relay 728, conductor 736, outer left back contact of relay 611, right contact of relay 628, conductor 629, upper winding of relay 805, to battery at the back contact of relay 806. Relay 805 operates and closes a locking circuit through its lower winding and the winding of relay 806, the latter relay operating in this circuit.

Relay 806 causes the operation of the multicontact relay 801 individual to the sender in a circuit from battery, through the winding of the latter relay, upper contact of relay 805, back contact of relay 807, to ground at the contact of relay 806. Relay 806 also closes a start circuit for selecting the first idle marker. Assuming that the marker shown, which is individual to the relay 804, is the first idle one, this start circuit leads from ground, through the contact of relay 806, conductor 811, contact of relay 807, front contact of relay 812 which is assumed to be operated, back contact of relay 813, upper back contact of relay 808, upper winding of relay 809, to battery at the contact of relay 810.

Relay 809 operates and closes a locking circuit through its lower winding and the winding of relay 810, to ground over conductor 811. Relay 810 operates in this circuit and closes operating circuits for relays 808

and 804. The circuits for these relays leads from ground, through the contact of relay 810, thence in parallel through the lower winding of relay 808 and through the winding of relay 809 and the winding of relay 804, to battery. Relay 810 also places ground potential on conductor 814 to identify the marker as busy. The sender is now connected to the idle marker and is ready to transfer the record of the office code through to the registers 900, 901, 902 and 903 of the marker.

In the manner described in U. S. Patent No. 1,600,399, issued September 21, 1926, to W. W. Carpenter, the record is transferred from the registers 700, 701, 702 and 703 to the corresponding registers 900, 901, 902 and 903 of the marker. All of the relays of the registers 900, 901, etc., are operated in circuits leading either through the front or back contacts of the corresponding relays of the sender registers, and a circuit is thereupon completed for relay 913. This circuit may be traced from battery, through the winding of said relay, thence through series contacts of all the marker relay registers, conductor 916, through the outer right back contact of relay 1006, to ground at the outer left contact of the holding relay 1001.

It will be noted that relay 1001 was operated at the time the sender connector 800 operated, by means of a circuit which may be traced as follows: Battery, through the winding of said relay, normal contacts thereof, conductor 1015, through the sender connector 800, to the grounded conductor 629. The relay 1001 is locked in a circuit from battery, through its winding and front contact, conductor 1016, back contact of relay 1017, conductor 1018, inner back contact of relay 1004, conductor 1019, to ground at the back contact of relay 1020.

When relay 913 operates as above described, it locks through its inner right contact to ground on conductor 916. Relay 913 closes an obvious circuit for relay 915, which operates and locks to conductor 916. Relay 915 opens the locking circuit of relay 913. Relay 913 at its back contact opens the circuits of all register relays 900, 901, etc., and these relays all release with the exception of those relays which correspond to energized relays in the sender. From inspection it will be found that none of the relays of register 900 are operated, whereas relays 917, 918, 919 and 921 of the registers 901, 902 and 903 are energized. Relay 913 now becomes released, since both its operating and locking circuits are opened.

The translator relay 906 is now operated in a circuit from battery, through the winding of this relay, back contacts of the register relays 900, conductor 920, contact of relay 915, to the grounded conductor 916. Relay 912 will also operate in a circuit from

battery, through its winding, front contacts of relays 919 and 921, back contacts of relays 922 and 923, to the grounded conductor 920. Relay 908 is operated in a circuit from battery, through its winding, contact of relay 912, back contact of relay 924, front contact of relay 918, back contacts of relays 925 and 926, to the grounded conductor 920. Relay 927 is also operated in a circuit from battery, through its winding, front contact of relay 917, back contacts of the remaining three relays of register 901, to the grounded conductor 920.

Since the connection being extended is one which leads through a tandem office, the marker sends certain class information back to the sender at this time in order that the sender may be prepared to transmit the necessary designation impulses to the tandem office. This information consists in the operation of certain class relays in the sender from the translator 905; for instance, the class relay 610 in the sender is operated to indicate to the sender that the call is one leading through a tandem office. The circuit for operating this relay may be traced from battery, through its winding, thence through the connector 800, conductor 816, contacts of relays 906 and 908, lower contact of relay 927, conductor 928, inner left contact of relay 1017, to the grounded conductor 1018. Also the class relay 635 is operated in a circuit from battery, through its winding, conductor 636, connector 800, conductor 822, to ground at the contact of relay 931. Furthermore, if it is assumed that the tandem office is equipped with full automatic switching apparatus, the class relay 616 in the sender is operated in a circuit from battery, through its winding, conductor 637, connector 800, conductor 823, to ground at the contact of relay 931. It will be noted that relay 931 is energized in a circuit leading through the translator 905 and contacts of relay 927. It will be understood that all class relays in the sender lock in order that they may remain energized after the marker is discharged. Other class relays may also be operated in the sender depending upon other factors concerned with the particular call in question. For a more complete description of the manner in which class indications are given to the sender, reference is made to U. S. Patent No. 1,517,331, issued Dec. 2, 1924, to S. B. Williams.

With the translator 905 set, one of a number of trunk group relays 1012, 1013, etc. is selected and operated to identify the particular group of trunks which leads to the desired tandem office. In this case, the relay 1012 is operated in a circuit from battery, through its winding, conductor 1022, through contacts of the translator 905, to the grounded conductor 928.

The frame connector 1100 is next operated

to associate the marker with the particular semi-mechanical district frame in which the trunk 132 appears. For this purpose, relay 1102 is operated in a circuit from battery, through its winding, conductor 1115, contact 70 of relay 915, conductor 929, connector 800, conductor 817, contact of the frame test relay 618, conductor 631, conductor 737, connector 800, conductor 818 and thence to the grounded conductor 916. For a more complete description of the manner in which the frame test is accomplished, reference is made to U. S. Patent No. 1,600,443, issued September 21, 1926, to S. B. Williams.

Relay 1102 completes a circuit from battery, through the right winding of relay 1103, contact of relay 1102, contact of relay 1116, back contact of relay 1106, to ground at the back contact of slow-release relay 1105. Relay 1103 operates and at its right 80 contact closes an operating circuit for the relay 1105. Relay 1105 opens the circuit of relay 1103, but the latter relay being slightly slow to release does not deenergize at this time. When relay 1105 closes its front contact, relay 1103 locks through its left winding and the winding of relay 1106, the latter relay operating in this circuit. Relay 1106 opens the circuit of relay 1105, and relay 1105 thereupon releases its armature. The 90 multi-contact relay 1104 is now energized in a circuit from battery, through its winding, contacts of relays 1103, and thence to ground at the back contact of relay 1105.

With relay 1105 released, relays 1103 and 100 1106 remain locked in a circuit which leads through the lower front contact of relay 1106, front contact of relay 1103, conductor 1118, to the grounded conductor 916.

The vertical magnet 211 controlling the row 105 of contacts 204 at the district switch 200, is operated in a circuit from battery, through its winding, thence through the lower back contact of relay 109, conductor 138, sender selector 500, conductor 535, conductor 632, 110 thence through the connector 800, conductor 819, normal contact of relay 1007, conductor 1023, through contacts of the frame connector 1100, to the grounded conductor 1118. Magnet 211 rotates the bar 208 and 115 prepares the contacts in vertical row 204. Magnet 211 at its inner lower contact also closes an energizing circuit for the multi-contact relay 1107, which is individual to the district frame 200. With the frame connector 1100 operated, a circuit is closed for operating the relay 1007, traceable from battery, through the winding of said relay, conductor 1024, thence through the frame connector 1100 to the grounded conductor 1118. Relay 1007 completes locking circuits for magnet 211 and relay 1107 traceable from battery, through the windings and contacts of said magnet and said relay, conductor 1120, contact of relay 1104, conductor 120 125 130

1121, front contact of relay 1007, to ground over conductor 1023 as above traced.

Next the trunk connector 1101 is operated to associate the marker with the proper

5 group of trunks outgoing from the district selector switch 200. For this purpose relay 1108 is operated in a circuit from battery, through its winding, contact of relay 1012, conductor 1025, front contact of relay 1103,

10 front contact of relay 1106, to ground at the back contact of relay 1105. In the same manner as described in connection with the frame connector 1100, the relay 1108 causes the operation of relay 1109 and also relays

15 1111 and 1112, and consequently the operation of multi-contact relay 1110. Relay 1113, which is individual to the particular group of trunks to be used, is also operated in a circuit from battery, through its winding,

20 thence through contact of the group relay 1012, conductor 1026, front contact of relay 1109, to ground at the back contact of relay 1111. The set of test relays 1000 is now connected to the group of trunks appearing

25 in the vertical row 207 of the switch 200 and also to the horizontal test links for testing to select an idle cross-point through the switch.

At the time ground is placed on conductor

30 916, relays 1011, 1027, etc., are operated in parallel in a circuit traceable over conductor 1028, through the middle right contact of relay 1008, normal contact of relay 1005, to the grounded conductor 916. With relays

35 1011 and 1027, etc., operated, all of the double wound test relays 1029, 1030, 1031, etc., are operated in circuits which may be traced from battery, through the right front contact of relay 1017, thence through the left

40 windings of relays 1029, 1030, etc., in parallel, thence through front contacts of relays 1011 and 1027, conductor 1032, to ground at the normal contact of relay 1002. With all of the test relays operated, a circuit is closed

45 for operating relay 1003, traceable from battery, through the winding of this relay, inner right back contact of relay 1008, thence through front contacts of relays 1029, 1030, 1031, etc., conductor 1033, outer right back

50 contact of relay 1008, middle right contact of relay 1008, to ground as above traced. Relay 1003 operates and closes an obvious circuit for relay 1002, which in turn operates and locks through its left contact to

55 the grounded conductor 916. Relay 1002 opens the original energizing circuits of the test relays but substitute circuits are provided which may be traced through the left hand windings and locking contacts of said

60 test relays, front contacts of relays 1011, 1027, etc., conductor 1034, to ground at the right front contact of relay 1002.

65 After both the frame and trunk connectors 1100 and 1101 have operated, a circuit is completed for operating the vertical magnet

212 of the selector 200, controlling the vertical row of contacts 207 in which appear trunks 215, 216, and 217 of the group leading to the desired tandem office. The circuit for this purpose may be traced from 70 battery, through the winding of said magnet, thence through the frame connector 1100, conductor 1123, contacts of relay 1012, conductor 1035, contacts of the trunk connector 1101, to the grounded conductor 1118. 75 With the vertical magnet 212 operated, a circuit is closed for the relay 1008 traceable from battery, through the winding of said relay, conductor 1036, frame connector 1100, thence to ground at the front contact of magnet 212. Relay 1008 releases relay 1003 and also all of the relays 1011, 1027, etc. The test relays 1029, 1030 and 1031 corresponding to idle cross-points in the switch 200 will release, but all relays which correspond to busy horizontal links 201, 202 and 203 or to busy outgoing trunks 215, 216 and 217 will remain energized. 80

Assuming that the trunk 217 and the link 203 are both busy, the relay 1029 in the marker corresponding to this cross-point will remain energized in a circuit from battery, through the right winding and front contact of relay 1029, conductor 1037, trunk connector 1101, to the grounded sleeve conductor of the trunk 217. Furthermore, a holding circuit for relay 1029 leads from battery, through its left winding and locking contact, lower normal contact of relay 1011, conductor 1038, through the trunk connector 1100, conductor 218, to the grounded sleeve conductor of the busy horizontal link 203. Similarly, if the trunk 216 is busy, or if link 202 is busy, or both are busy, the relay 1030 remains operated. 95

Assuming, however, that the trunk 215 and the link 201 are both idle, relay 1031 releases. Relays 1009 and 1039 are now operated in a circuit from battery, through the winding of relay 1009, thence through the winding of relay 1039, back contact of relay 1031, front contacts of relays 1030 and 1029, front contact of relay 1008, to ground upon the back contact of relay 1010. Relay 1039 closes a locking circuit for itself and relay 1009 traceable through the inner right front contact of relay 1039 to the grounded conductor 916. Relay 1039 also closes an obvious circuit for relay 1010. 110

The horizontal operating magnet 219 is 120 now operated to complete the connection from the trunk 132 through the switch 200 to the idle trunk 215 leading to the distant tandem office. The circuit may be traced from battery, through the right winding 125 of magnet 219, conductor 220, frame connector 1100, thence through the middle left contact of relay 1039, to ground at the front contact of relay 1010. When the switch 200 has fully operated, relay 109 in the opera- 130

tor's cord circuit is energized by means of a circuit from battery, through the winding of said relay, thence over the sleeve conductor of trunk 132, through contacts of the 5 switch 200, conductor 221, trunk connector 1101, conductor 1124, right back contact of relay 1031, front contacts of relays 1030 and 1029, to ground at the front contact of relay 1008. Relay 109 locks in a circuit traceable 10 to ground at the left front contact of relay 127. The horizontal magnet 219 also locks in a circuit through both its windings, contacts of switch 200 to ground over conductor 132 through contacts of relay 109 as traced. 15 The marker release relay 1006 is also operated in a circuit from battery, through its winding, conductor 1040, front contact of relay 1039, conductor 1041, frame connector 1100, through contacts of the selector 200, 20 and thence to ground as above traced over conductor 221. Relay 1006 locks to ground at the outer left contact of relay 1001. Relay 1006 closes an obvious circuit for relay 1017. Relay 1017 causes the release of the 25 various energized test relays and also of other energized relays in the marker. Relay 1017 also causes the release of the frame connector 1100 and the trunk connector 1101. Relay 1006 causes the operation of the 30 relay 611 in the sender, indicating to the sender that the marker has completed its functions and is about to become released. The circuit for this relay may be traced from battery, through the winding thereof, 35 conductor 633, connector 800, conductor 820, contact of relay 1009, to ground at the inner left contact of relay 1006. Relay 611 locks to the grounded conductor 621. Relay 611 opens the original energizing circuit of relay 40 805, causing the release of the sender connector 800. The marker is now completely restored (all relays therein having been released) and is ready for use in connection with a subsequent call. 45 Since the class relays 610, 635 and 616 are operated in the sender, the sender is prepared to transmit impulses to the distant tandem office representing the routing code of the called office. With relay 611 operated, a circuit is completed from the 50 grounded conductor 736, outer left front contact of relay 611, right back contact of relay 613, right front contact of relay 635, inner right contact of relay 616, outer left contact of relay 638, thence over conductor 639 to a relay (not shown) which may serve to start the impulse transmitting mechanism of the sender in operation. For a disclosure of a sender having impulse transmitting 55 mechanism for sending impulses to distant tandem offices under conditions of this kind, reference is made to U. S. Patent No. 1,543,967 issued June 30, 1925, to S. B. Williams and E. S. Gibson. 60 After the impulses have been transmitted to the distant office, the sender and sender selector 500 are released. The release of the sender causes the release of relay 110 in the trunk circuit, which completes the tip and ring conductors of the trunk 132 through to 70 the right hand winding of the repeating coil 104. Relay 110 also extinguishes the white supervisory lamp 111. When the called subscriber answers, the relay 140 is energized and closes a circuit for 75 relay 123. This circuit may be traced from battery, through the winding of relay 123, the right back contact of relay 117, to ground at the front contact of relay 140. Relay 123 locks to ground at the contact of relay 127. 80 Relay 123 opens the circuit for the green supervisory lamp 121 which ceases to glow. If the operator desires to listen out, she may do so by manipulating her listening-out key 303. This key closes a circuit from 85 ground, through its left contact, thence over conductor 304, through the left contact of relay 114 and resistance 301, to battery. It will be noted that this circuit is in shunt of the relays 130 and 131, which latter relays 90 become released and cause the release of relay 105, which in turn causes the disconnection of the operator's telephone set from the cord circuit 103. At the end of the conversation when both 95 parties hang up their receivers, relays 113 and 140 become deenergized. Relay 115 releases and a circuit is closed for illuminating the red supervisory lamp 129. This circuit may be traced from battery, through the lamp, resistance 133, to ground at the contact of relay 127. The white lamp 111 is also lighted in a circuit from battery, through said lamp, resistance 112, inner 100 right back contact of relay 116, left contact of relay 123, to ground at the back contact of relay 140. The operator receives the disconnect signal and removes the plug 102 from the jack 101 of the trunk 100, causing 105 the release of the apparatus. The removal of the plug from the jack causes the release of the sleeve relay 127, which removes ground from the various holding conductors, permitting the release of the relays 110 dependent thereto, including relay 109. 110 Should the operator desire to route the connection through another tandem office to the called office, she will depress the route key 420 corresponding to such other tandem office, together with the same code keys 407, 408 and 409 and numerical keys in the section 404. Since a new routing key 420 is 120 operated, the record set up on the routing register 700 in the register and correspondingly on the routing register 900 in the marker, differs from that previously assumed. In this case, it will be assumed that the record is such that the translator causes the selection and operation of tandem routing group relay 1013. Relay 1013 may cause 125 130

the selection of a group of trunks appearing in the vertical row 206 of the district selector which lead to the desired tandem point. From this point on, the operation of the marker and the testing and operation of the selector switch to extend the connection over the selected trunk and the transmission of impulses, may take place in substantially the same manner as hereinbefore described in detail.

Thus it will be seen that the operator is provided with a number of routing keys which she may use to extend connections by way of different routes to any desired office within the range of these tandem points.

What is claimed is:

1. In a telephone system, a selective switch, a register sender, an operator's position, means controlled by the operator for variably setting said sender, a marker associative with said switch for selectively actuating the same, means for connecting said sender to said marker and for transferring thereto a record of the setting of said sender, a wanted telephone line, a plurality of routes from said switch to said line, and means in said marker dependent upon the setting thereof for controlling said switch to select a desired route to said line.
2. In a telephone system, a selective switch, a register controlling sender, an operator's position and a keyboard thereat, a marker for selectively controlling the operation of said switch, means for associating the sender with the marker, means operable in accordance with the manipulation of the operator's keyboard for establishing a record in the sender to in turn establish a corresponding record in the marker, a called line, a plurality of paths leading from said switch toward said line, and means in the marker dependent upon the record established therein for controlling said switch to select a desired one of said paths.
3. In a telephone system, a selective switch, a register sender, means for variably setting said sender, a marker for selectively operating said switch, means for connecting

the sender to the marker and for variably setting said marker in accordance with the setting of said sender, a called office, a plurality of tandem offices, paths leading from said switch through each of said tandem offices toward said called office, and means in said marker dependent upon the setting thereof for controlling said switch to select the desired one of said paths.

4. In a telephone system, a selective switch, a plurality of register senders, an operator's position, means controlled by the operator for variably setting any one of said senders, a plurality of switch controlling markers each associative with said switch for selectively actuating the same, means for associating any sender with any marker and for transferring to such marker the setting of the connected sender, a called line, a plurality of routes leading through such switch toward said line, and means dependent upon the setting taken by said marker for governing the operation of said switch to select a desired one of said routes.

5. In a telephone system, a selective switch, an operator's position, a cord circuit at said position terminating in said switch, a number of distant offices, trunks leading through said switch to each of said distant offices, a called office accessible to each of said distant offices, a register sender associative with the operator's position and means controlled by the operator for variably setting said sender, a switch controlling marker for selectively operating said switch, means for setting said marker in accordance with the setting of said sender, and means dependent upon the setting taken by the marker for governing the operation of said switch to extend a connection over a trunk leading through a desired distant office to said called office.

In witness whereof, we hereunto subscribe our names this 14th day of November A. D., 1924.

SAMUEL B. WILLIAMS.
EARL S. GIBSON.
